UNITED STATES PATENT OFFICE

THOMAS A. EDISON, JR., OF EAST ORANGE, AND HENRY S. CARLSON, OF ORANGE, NEW JERSEY, ASSIGNORS TO THOMAS A. EDISON, INCORPORATED, OF WEST ORANGE, NEW JERSEY, A CORPORATION OF NEW JERSEY

DESIGN FOR A TOASTER OR LIKE ARTICLE

Application filed December 13, 1932. Serial No. 46,457. Term of patent 7 years.

To all whom it may concern:

Be it known that we, THOMAS A. EDISON, Jr., a citizen of the United States, and a resident of East Orange, county of Essex, State of New Jersey, and HENRY S. CARLSON, a citizen of the United States, and a resident of Orange, county of Essex, State of New Jersey, have invented a new, original, and ornamental Design for a Toaster or like Article, of which the following is a specification, reference being had to the accompanying drawings, forming a part thereof.

In the drawings:

Figure 1 is a perspective view of a toaster or like article showing our new design;

Fig. 2 is a top plan view of the toaster or like article shown in Fig. 1; and

Fig. 3 is an end elevational view of the toaster or like article looking from the right in Fig. 2.

We claim:

The ornamental design for a toaster or like article, substantially as shown.

THOMAS A. EDISON, JR.
HENRY S. CARLSON.
